TYPEWRITING MACHINE

Miles H. Mann, West Hartford, Conn., assignor to
Underwood Corporation, a corporation of Delaware

Application December 31, 1941, Serial No. 425,109

24 Claims. (Cl. 197—2)

This invention relates to typewriting machines and more particularly to such machines in which the work sheets are supported upon a substantially flat platen. Certain features of the invention are particularly adapted to be embodied in flat platen typewriting machines of the Elliott-Fisher type comprising a substantially horizontal flat platen and type bar actuating mechanism in which each type is projected downwardly during its operating stroke and moves in a direction substantially perpendicular to the work supporting surface of the platen adjacent the end of said stroke.

In typewriting machines of the Elliott Fisher type having types of different case, type heads each having different case types mounted thereon are usually pivoted on certain of the type bars and a type shifting disc is arranged to be moved by a suitable key into and out of position to be engaged by an arm on the type head during the actuating stroke of a type bar to shift said head. In such machines, of which applicant is informed, the construction has been such that the upper case types have engaged the work sheets with substantially the same force as the lower case types.

One object of the present invention is to improve the construction and mode of operation of the case shift mechanism for flat platen typewriting machines and to produce a machine in which, with substantially uniform type bar actuations, the force with which the types engage the work sheets in lower and upper case positions of said mechanisms may be relatively varied.

Another object of the invention is to provide machines of this class with a novel and improved type bar and case shift mechanism in which the type bars are supported on a type bar segment mounted for movement to shift case.

Another object of the invention is to produce a type bar mechanism for flat platen machines in which the type bars are supported on a type segment mounted for movement to shift case and having a novel type bar actuating mechanism whereby substantially uniform actuations of a type bar mechanism will cause the types to engage the work with the required force whether the supporting segment is in lower case or in upper case position.

Another object of the invention is to provide type-writing machines of the flat platen type with novel mechanism for shifting the type bar mechanisms from lower to upper case positions by power and for also shifting said mechanisms by power back to lower case positions.

Another object of the invention is to produce improved type bar mechanism for flat platen machines comprising a shiftable type bar segment upon which the type bars are pivoted whereby respectively upon the depression and upon the release of a shift key, the type bar segment

will be shifted into upper case position by power and will be shifted by power back to its lower case position.

Another object of the invention is to produce a type bar mechanism for machines of the type having a substantially flat platen in which each type bar is started slowly and easily in its type impression stroke, is accelerated as it approaches a work sheet supported on the platen and is locked against rebound when retracted to starting position and in which the several type bars are mounted upon a type bar segment arranged to be shifted from one position to another to shift case.

With the above and other objects in view the invention consists in a machine embodying the novel and improved features, constructions and combinations of parts hereinafter described and particularly pointed out in the claims, the advantages of which will be readily understood and appreciated by those skilled in the art.

The various features of the invention will be clearly understood from the accompanying drawings illustrating a machine embodying the invention in its preferred form and the following detailed description of the constructions therein shown.

In the drawings:

Fig. 1 is a view in vertical section through the type carriage of a typewriting machine of the so-called Elliott Fisher type embodying the invention, with certain portions broken away and illustrating the type bar mechanism or type action corresponding to one of the central type bars of the segmental group of type bars with the parts in lower case positions and with the type bar retracted;

Fig. 2 is a detail view in vertical section illustrating a type bar mechanism corresponding to a type bar at one end of the segmental group of type bars with the parts in lower case positions and with the type bar retracted;

Fig. 3 is a detail view in vertical section illustrating the type bar mechanism shown in Fig. 1 with the parts in upper case positions and the type bar retracted;

Fig. 4 is a detail plan view illustrating the type bar mechanisms shown in Figs. 1 and 2 with the parts in lower case positions and with the type bars advanced into positions to engage one of the types of each bar with the work;

Fig. 5 is a view similar to Fig. 3 illustrating the type bar mechanism shown in Fig. 3 with the parts in lower case positions and the type bar advanced into position to engage one of the types thereof with the work;

Fig. 6 is a view similar to Fig. 5 illustrating the same type bar mechanism with the parts in upper case positions and also with the type bar advanced into position to engage one of the types thereof with the work.

Fig. 7 is a detail plan view illustrating the shiftable type segment for supporting the shiftable parts of the type actions and certain associated parts.

Fig. 8 is a detail view in side elevation, with certain parts in section, illustrating particularly the shiftable segment for the type actions and the mechanism for shifting the same.

Fig. 9 is a view in front elevation partly broken away and partly in section illustrating certain parts of the mechanism shown in Fig. 8.

Fig. 10 is a detail view illustrating, in side elevation, parts of the mechanism shown in Fig. 8.

Fig. 11 is a detail view in front elevation, illustrating the mechanism shown in Fig. 10 and certain associated parts.

Fig. 12 is a detail view in side elevation with certain parts in section, illustrating a portion of the mechanism shown in Fig. 8 with certain of the parts in different positions.

Fig. 13 is a detail view in side elevation illustrating certain parts of the driving mechanism.

Figs. 14, 15, 16 and 17 are diagrammatic views illustrating the mode of operation of different forms of the type bar mechanism in upper and lower case positions, and

Fig. 18 is a view in side elevation illustrating a modified form of type bar mechanism corresponding to one of the central type bars of the segmental group of type bars.

The invention is shown in this application as embodied in a typewriting machine of the so-called Elliott Fisher type having its parts constructed and arranged, except for the type bar and case shift mechanisms, substantially as illustrated and described in the co-pending application of Oscar J. Sundstrand, Serial No. 281,772, dated June 29, 1939 which matured as Patent No. 2,370,505 February 27, 1945.

This machine comprises a rectangular platen frame (not shown), a substantially flat platen 2 mounted for vertical movement in said frame, a line space frame mounted on the side bars or rails of the platen frame for forward and rearward movement over the platen and having front and rear rails 4 and 6, and a type carriage 8 mounted for lateral movement over the platen 2 by means of front and rear sets of rollers 10 and 12 arranged to engage said rails.

The type carriage carries a series of type bars and operating mechanism therefor in which each type bar is mounted upon the type carriage and actuated to project the same downwardly into engagement with a work sheet supported on the platen, each type carried by the type bar moving substantially perpendicular to the platen adjacent the end of its type impression stroke. In the construction illustrated, power operated mechanism is provided for actuating the type bars. The principal features of the case shift mechanism, however, are not limited to a machine in which the type bars are actuated by power but may be embodied with advantage in machines in which the type bars are actuated by the hands of the operator.

The type bars and certain parts of the mechanisms for actuating the type bars are mounted upon a type bar segment shiftably supported upon the type carriage and arranged to be moved from one operative position to another to shift case. This type bar segment comprises a segmental plate indicated at 14 and preferably having the shape in cross section shown clearly in Fig. 1. Fig. 7 shows clearly the arcuate or segmental form of this plate in plan. The plate

14 is provided with a series of radially arranged slots 16 in which are pivoted upon an arcuately bent pivot rod 18 passing through the tongues 20 between the slots, a series of type bars or levers 22. The center of the arc of the pivot rod 18 and the corresponding arc of the segmental plate 14 is located adjacent the typing point and preferably slightly to the rear thereof when the type bar segment is in lower case position. Each of the type bars 22 preferably consists of a relatively thin sheet metal plate, stamped or cut to the form shown in Fig. 1 and having a type head 24 provided with one or more types arranged to engage the work sheet supported on the platen 2. The segmental plate 14 preferably consists of a casting made of some light metal such as aluminum or an aluminum alloy.

The type segment comprises a support 26 also preferably consisting of a casting of some light metal such as aluminum or aluminum alloy, and this support is provided with an arcuate portion 28, the arc of which is substantially parallel with the arc of the pivot rod 18 and that of the segmental plate 14 and said support is formed with a series of radial slots 30 arranged respectively opposite the slots 16 in the segmental plate 14, said support 26 being located a substantial distance above the arcuate plate 14 as clearly shown in the drawings. Within the respective slots 30 in the support 26 are pivoted a series of levers 32 upon an arcuate pivot rod 34 passing through the tongues 36 located between said slots, the arc of this rod being substantially parallel with the arc of the pivot rod 18. Each of the bell crank levers 32 is connected by a link 38 with a projecting tail portion 40 formed on each of the type bars.

The support 26 of the type bar segment is formed with a bar-like portion 42 preferably integral with the arcuate portion 28 and extending rectilinearly across the segment. This bar-like portion 42 is formed with a series of substantially parallel slots 44 in which respectively are pivoted a series of bell crank levers 46 upon a rectilinear pivot rod 48 passing through the tongues 50 between the slots 44. The axis of this rod is substantially parallel with a line tangent to the axis of rod 34. These levers 46 are respectively connected by means of links 52 with the bell crank levers 32. The arcuate portion 28 and the bar-like portion 42 with the pivot rods 34 and 48 passing through the same are arranged above the segmental plate 14 as shown in Figs. 1, 2, 5 and 6.

The bell crank levers 46 are connected respectively by means of links 54 with the bell crank levers 56 pivoted upon a rectilinear pivot rod 58 supported in the frame of the type carriage and extending across the same substantially parallel with rod 48 considerably above the type bar segment. The bell crank 56 is provided with a slot 60 in which engages a roll 62 fixed to a relatively long intermediate lever 64 pivoted at its rear end upon a rectilinear pivot rod 66 extending across the type carriage substantially parallel with rod 48 and supported on the frame of the carriage, these levers 64 being substantially parallel with each other.

The bell crank lever 32 is acted upon by a coiled spring 67 which tends to swing the same downwardly about its pivot to retract the type bar. To the lever 64 is connected a coiled spring 69a which tends to swing the same upwardly and to maintain the forward end of the lever in engagement with a buffer 71. By the action of the springs 67 and 69a together with the cooperating spring of

the power driven mechanism for actuating the lever 64, each type bar mechanism is restored to retracted position after a type impression stroke.

The segmental plate 14 and the support 26 are secured together in the relation shown in plan in Fig. 7 and in cross section in Fig. 1, by means of the side plates 68 located outside of said segmental plate and said support, and secured to these parts by suitable screws indicated at 70.

The type bar segment is pivoted to swing vertically upon a substantially horizontal axis to shift the type bar mechanisms between lower case and upper case positions. To this end, each of the plates 68 is provided at its forward end with a bearing sleeve 69 mounted in an opening in the plate and held from turning therein by means of a key (not shown) formed on the plate engaging in a suitable keyway or groove extending longitudinally of the sleeve. The sleeve 69 is secured in the plate 68 for longitudinal adjustment therein by means of a cap nut 71 threaded on the inner end of the sleeve and a nut 72 threaded on the sleeve outside of the plate 68. The type bar segment is pivoted upon bearing pins 73 each of which is threaded into a tubular boss or support 75 fixed in one of the uprights 74 (Fig. 1) of the frame of the type carriage connecting the horizontal plates 76 and 77 of said frame. Each of the pins 73 projects inwardly from the boss 75 into the bearing sleeve 69 to support the type segment and the type segment is held in position longitudinally of its axis by the engagement of the bosses 75 with the outer ends of the bearing sleeves 69.

The manner of mounting the bearing sleeves respectively in plate 68 enables said sleeves to be readily adjusted axially in the plates. In this manner the type segment may be adjusted axially so as to adjust the typing position of the type heads laterally of the machine. This adjustment may be effected by loosening the cap nut 71 or the nut 72 or both said nuts and then positioning the sleeve 69 axially in the plate 68 after which both the nuts are tightened to secure the sleeve firmly in position.

The axis of the type bar segment is located immediately above the typing point or line. The parts of the type bar mechanisms are arranged so that, in the case of certain type bars, the type bar will be given substantially the same actuation or movement under the action of the actuating mechanism when the type segment is in upper case position as when the type segment is in lower case position so that the type will engage the work sheet with substantially the same pressure or force. The parts of the type bar mechanism may be constructed and arranged so that the upper case types will engage the work with substantially the same force as the lower case types in all of the 42 or more bars of the type basket. Preferably, however, the construction and arrangement is such that the upper case letter types, which are ordinarily somewhat larger in area than the lower case letter types, will strike the work sheet with a slightly greater force than the lower case types to produce substantially uniform type impressions with all the letter types.

The parts of the several type bar mechanisms between the levers 64 and the type bars may be varied in constructions and dimensions in different ways to obtain substantially uniform actuations of the type bars from these levers. Certain of these variations which have been employed in actual practice and have secured satisfactory results are indicated generally below.

The type bars 22 have substantially the same

lengths throughout the type segment but the type heads 24 are bent at different angles with relation to the type bars to cause each type to engage the work in a position substantially perpendicular to the type line. The links 38, the bell cranks 32, and the links 52 also preferably have substantially the same dimensions throughout the type segment. The bell crank levers 46 vary in dimensions from the central portion to the outer portion of the type segment. In these levers, considering the levers in normal positions with the type bars retracted, the horizontal distance between the pivot 82 connecting the link 54 with the lever and the pivot 48, in general, increases slightly in successive levers from the central portion to the outer portion of the segment although there are certain exceptions to this rule. There is also, in general, a greater increase in the vertical distance between the pivot 48 and the pivotal connection 82 in successive levers from the central portion to the outer portion of the segment. The horizontal distance between the pivot 48 and the pivotal connection 84 between the link 52 and said lever is increased to a still greater extent in successive levers from the central portion to the outer portion of the segment.

The length of the link 54 between the pivotal connection 82 connecting the same with the lever 46 and the pivotal connection 88 connecting the link with the lever 56 increases in successive type bar mechanisms from the central portion to the outer portion of the type bar segment. In the case of the lever 56, the horizontal distance between the pivot 58 of the lever and the center of the pivotal connection 88 between the same and the link 54, in general, is increased slightly in successive type bar mechanisms from the central to the outer portion of the type bar segment. The vertical distance between the pivot 58 of the lever 56 and the center of the pivotal connection 88 diminishes greatly in successive type bar mechanisms from the central portion to the outer portion of the type bar segment while the length of the horizontal arm of the lever is substantially increased in said successive type bar mechanisms.

The levers 64 have substantially the same length throughout the series. The distance, however, between the pivot of the lever and the center of the roll 62 is increased, generally, in the successive type bar mechanisms from the central portion to the outer portion of the type bar segment although there are certain exceptions.

In the machine illustrated in this application, the levers 64 are swung downwardly by power under control of suitable keys of the keyboard to actuate the type bars.

Certain of the type bars 22 of the present machine are provided with a plurality of types arranged to be brought alternatively into position to engage a work sheet supported on the platen and all of the type bars may be provided with this construction if desired. As shown in Figs. 1, 3, 5 and 6 of the drawings, the type bar 22 is provided with two types 90 and 92 arranged at different distances from the axis of the type bar and having the type axes arranged at an acute angle to each other and the acting faces of the types at an obtuse angle. With the type bar segment in lower case position, the angular position of the type bar with relation to the platen is such that the type nearer the axis of the type bar will be engaged with the work sheet when the type bar is swung into type engaging position as shown in Fig. 5. With the type bar segment in upper case position, however, the angular position of

the type bar with relation to the work sheet is shifted so that the type 90 farther from the axis of the type bar will be engaged with the work sheet, when the type bar is swung into work engaging position, the other type being held out of engagement with the work sheet as shown in Fig. 6.

The construction and operation of the type bar mechanism can be better described by drawing a line 94 through a point 93 in the axis of the type bar segment and a point in the axis of the pivotal connection 88, and continuing said line beyond said pivotal connection 88. The line 94 or any other equivalent line of a type bar mechanism may, for convenience, be termed the median line of the type bar mechanism. The construction of the type bar segment and the type bar mechanisms are preferably such that, with the type bars in retracted positions, the pivotal connections 82 are located the same distances below the lines 94 when the type bar mechanisms are in lower case positions that these connections are located above said lines when the type bar mechanisms are in upper case positions. Each of these lines bisects the angle between the upper and lower case positions assumed by the link 54 of the corresponding type bar mechanism when the type bar is retracted. In all cases in which it is desirable that a type bar mechanism shall produce substantially the same action or that the type shall strike the work sheet with substantially the same force when the type bar mechanism is in upper case position as when said mechanism is in lower case position, the parts are constructed and arranged so that the center of the pivotal connection 88, in the actuation of a type bar, is moved from the point in the median line or bisector 94 which it occupies at the beginning of a type bar actuating stroke, to a point in said bisector at the end of said stroke both when the type bar mechanism is in lower case position and when said mechanism is in upper case position. This construction and mode of operation is shown in the diagrammatic views Figs. 14 and 15.

A slightly different arrangement of the parts of the type bar mechanisms is employed in those mechanisms in which it is desired that the type shall strike a heavier blow upon the work sheet when the type bar segment is in upper case position than when said segment is in lower case position. In this case the parts are constructed and arranged so that the center of the pivotal connection 88, during a type bar actuating stroke, is moved from the point in the median line or bisector 94 which it occupies at the beginning of a type bar actuating stroke to a point below said line at the end of said stroke. The type bar mechanism will have this mode of operation both when said mechanism is in lower case position and when said mechanism is in upper case position. Figs. 16 and 17 show, diagrammatically, this construction and mode of operation.

The construction and mode of operation shown in Figs. 14, 15, 16 and 17 will be further explained in the later description.

The machine is provided with a type head guide 95 for locating each type head laterally of the machine as the type head is projected downwardly to engage one of the types with the work and thereby insure the placement of the type in the proper lateral position in the printing line. This guide is attached at its forward end to the traverse portion of plate 71 of the frame of the type carriage extending in front of the typing point. The guide 95 is provided adjacent the rail

5 with a slot or guideway 96 having downwardly converging side walls arranged to receive a projection 97 extending outwardly from the type head beyond the type 98. This slot, which has only a slightly greater width than the projection 97 on the type head, is entered by the projection when the type segment is in lower case position. In order, correspondingly, to position the type heads when the type segment is in upper case position, the type head guide 95 is extended rearwardly beyond the typing point and is formed with a laterally deflected end portion 98 having a guide slot 99 formed with downwardly converging side walls to receive the projection 100 extending inwardly from the type head when the type segment is shifted to upper case position. The type bars 22 are preferably made of sheet metal for the sake of lightness and relatively low expense of manufacture and are easily bent laterally out of proper position. With the above construction, if the type head is slightly displaced out of its normal position laterally of the machine, the engagement of one of the projections 97 or 100 on the type head with one of the side walls of the corresponding slot in the type head guide during the type impression stroke of the type bar will deflect the type head laterally to place the corresponding type in the proper position laterally in the type line when it engages the work.

35 The segmental plate 14 of the type segment is provided with the usual whip ring 100a which is engaged by each of the type bars just before a type carried by the bar is engaged with the work sheet lying on the platen. The momentum of the outer portion of the type bar and the type head after the type bar engages the whip ring carries the type into engagement with the work sheet, the type bar springing during this action.

40 As above stated, in the present construction, power operated mechanism is provided for moving the lever 64 of each type bar mechanism downwardly to engage the types carried by the type bars with the work sheets. In this construction, the power mechanisms for operating the levers 64 have substantially the same construction, arrangement and mode of operation as the corresponding mechanisms for operating the intermediate levers of the type bar mechanisms shown and described in the patent to Oscar J. Sundstrand No. 2,370,505. This power mechanism comprises a radius bar 106 pivoted at 108 on a rod supported on the cover plate 110 of the type carriage, a transmitting link 112 connecting the radius bar with the lever 64, a driving link 114 having its lower end pivotally connected at 116 with the radius bar, a continuously rotating fluted shaft 118 and a pawl 120 mounted on the driving link and arranged to be engaged with the fluted shaft. The driving link 114 is acted upon by a coiled spring 121 which tends to swing the same about its pivotal connection with the radius bar to carry the pawl away from the fluted shaft, this movement being limited by an arresting plate 122 and the driving link is swung in the opposite direction to engage the pawl with the fluted shaft by means of a link 124 connected with the upwardly extending arm of a key lever 126 pivoted at 128 on the type carriage, said link 50 having a shoulder arranged to engage a pin 130 on the driving link to swing said link into position to engage the pawl with the fluted shaft. During the downward movement of the driving link to actuate the type bar, the upper end thereof is arranged to engage, at a point in the operation

of the type bar mechanism adjacent the end of the downward movement of the link, a contact plate 132 adjustably mounted on the supporting plate 134 for adjustment toward and from the driving link. The engagement of the driving link with the contact plate limits the swinging movement of the driving link toward the fluted shaft and causes the disengagement of the driving pawl from said shaft as said shaft continues its rotation. By the adjustment of the contact plate 132, the point in the movement of the driving link at which the driving pawl is disengaged from the fluted shaft may be adjusted to adjust the type impression. The fluted shaft 148 may be continuously rotated through any suitable driving connections.

In the present machine, power mechanism is provided for shifting the type bar segment from lower case to upper case position when it is desired to employ the upper case types and for shifting the type segment back to lower case position when it is desired to return to the use of the lower case types. This power mechanism is controlled by a suitable key so that, upon the depression of the key the type bar segment will be positively shifted into upper case position and upon the release of the key the type bar segment will be positively shifted back to lower case position.

In the construction shown, the mechanism for shifting the type bar segment comprises a rotatable shaft 136 mounted to rotate in suitable bearings 138 supported upon the side plates 140 of the type carriage. Upon the shaft 136 are fixed two gears 142 meshing with gears 144, the hubs of which are journaled upon bearing studs 146 and 148 respectively fixed to the side plates 140. To the gears 144 are attached discs 150 each having a crank pin 152 upon which is pivoted, at its upper end, a link or pitman 154, the lower end of which is pivotally connected by means of a stud 156 with the support 26 of the type segment. An eccentric adjustment is preferably provided between each link 154 and the corresponding disc 150 and also between the link and the support 26 of the type segment to enable the lower case and upper case positions of the segment to be vertically adjusted.

When the type bar segment is in lower case position, the parts of the mechanism for shifting the segment occupy the positions shown in full lines in Figs. 8 and 9 with the crank pins 152 in their lowermost positions. In shifting the type segment to upper case position, the shaft 136 is given a half revolution thereby shifting the crank pins 152 to their uppermost positions. In restoring the type segment to lower case position, the shaft 136 is given another half revolution to restore the parts to the positions shown in Figs. 8 and 9.

The mechanism for rotating the shaft 136 comprises a half revolution clutch mechanism controlled by a suitable case shift key. Upon the left hand end of the shaft 136 is fixed a clutch disc 158 upon which is pivoted, at 160, a clutch pawl 162 having a tooth 164 arranged to engage in any one of a series of slots or grooves 166 cut in one end of a sleeve 168 mounted on a reduced portion of the shaft 136 normally to turn freely thereon. The sleeve 168 is continuously driven during the operation of the machine. The pawl 162 is acted upon by a coiled spring 170 which tends to swing the same in a direction to engage the tooth 164 in one of the grooves 166 in the sleeve 168 and thereby connect the sleeve with

the shaft 136. The pawl is normally held in position upon its pivot with the tooth disengaged from the sleeve by means of a slide 172 mounted to slide vertically upon suitable supporting studs 174 engaging in slots 176 in the slide. This slide is formed with forwardly projecting arms 178 having laterally projecting fingers 180 arranged to be positioned alternatively in front of a radially extending arm 182 on the pawl 162.

10 The vertical position of the slide 172 is controlled from a key lever 184 pivoted on a shaft 186 extending across the machine, said lever being connected with the slide by means of a link 188 pivoted at its upper end to the lever and pivotally connected at its lower end with a stud 190 fixed to the slide as shown particularly in Fig. 11. The slide 172 is normally held in elevated position by means of a coiled spring 192 acting on the key lever 184. In order to prevent 15 retrograde movement of the disc 158 and the shaft 136, after the disengagement of the clutch, a pawl 194 is pivoted upon the upper stud 174 and is arranged to engage one of the shoulders 196 formed on the disc. The pawl 194 is acted upon by a coiled spring 198 which maintains the same in engagement with the edge of the disc.

When the type bar segment is in lower case position, as shown in Figs. 1, 2, 5 and 8, the slide 172 is located in elevated position with the lower finger 180 engaging the arm 182 on the pawl 162 to hold the pawl out of engagement with the sleeve 168. In order to shift the type bar segment to upper case position, the key lever 184 is depressed thereby moving the slide 172 downwardly and disengaging the lower finger 180 from the arm 182 on the clutch pawl and moving the upper finger downwardly into position to engage said arm, after a half revolution of the disc 158. Upon the release of the pawl 162, the tooth 164 on the pawl is engaged in one of the grooves 166 on the sleeve 168 and the pawl, the disc 158 and the shaft 136 are positively driven by the sleeve until the arm 182 on the pawl is engaged with the upper finger 180 on the slide 172. The engagement of the arm on the pawl with the finger turns the pawl on its pivot 160 to disengage the tooth 164 from the groove in the sleeve and thereby cause the arrest of the rotary movement of the disc 158 and the shaft 136 at the end of a half revolution of the shaft. This half revolution of the shaft shifts the pitman 154 to raise the type bar segment to upper case position. The type bar segment will be maintained in upper case position as long as the shift lever 184 is held depressed. Upon the release of said lever, the lever and the slide 172 are moved upwardly by the spring 192, thereby disengaging the upper finger 180 from the arm 182 on the clutch pawl 60 and moving the lower finger 180 into position again to engage said arm. The release of the arm 182 on the pawl allows the pawl to act to clutch the disc 158 to the sleeve 168 to drive the disc 158 and the shaft 136 through another half revolution at the end of which said arm is again engaged with the lower finger 180 on the slide 172 and the pawl is swung upon its axis to unclutch the same from the sleeve 168. This second half revolution of the shaft 136 shifts the pitmans 154 back to their lowermost positions and the type bar segment is thereby shifted positively to lower case position. Upon each unclutching of the disc 158 from the sleeve 168 and the stoppage of the rotary movement of the disc, retrograde movement of the disc is prevented by the 75

engagement of the pawl 194 with one of the shoulders 196 on the disc.

The mechanism for continuously rotating the sleeve 168 comprises a pulley 200 mounted upon a hub 202 fixed to the sleeve to rotate therewith by means of set screws 204. The sleeve is loosely mounted on the shaft 136 as above stated and is held longitudinally in position on the shaft by its engagement at one end with the disc 158 and by its engagement at the other end with a collar 206 attached to the end of the shaft. The pulley 200 is continuously driven by means of a belt 208 passing about said pulley and about a second pulley 210 fixed to a shaft 212 journaled in suitable bearings carried by the frame of the upper portion of the type carriage and carrying the fluted roll 118. To the pulley 210 or to the shaft 212 is fixed a second pulley 214 and this pulley is driven from an intermediate pulley 216 by means of a belt 218 passing about said pulleys. The pulley 216 is mounted on a shaft 217 to rotate therewith. To the shaft 217 is fast a second pulley 220 of somewhat larger diameter about which passes a belt 222 by which the pulley 220 is driven from a pulley 224 of still larger diameter. The pulley 224 is mounted on a shaft 226 upon which is fixed a gear 228 meshing with a gear 230 journaled on a shaft 232 substantially parallel with the shaft 226. To the gear 230 is fixed a pulley 234 about which passes a belt 236 through which the pulley 234 is driven from a pulley 238 fixed on the shaft 240 of an electric motor 242. The shaft 217 is held from movement transversely of the machine and the pulley 216, while mounted to rotate with the shaft, is slidable longitudinally of the shaft to accommodate the transverse movements of the type carriage.

The type segment is acted upon by coiled springs 199 each attached to one end of a bracket 201 secured to the plate 76 and at its other end to one of the plates 68. These springs counter-balance the weight of the type segment and enable the same to be lifted more easily by the power mechanism.

As stated above, in the case of certain type bar mechanisms, it is desirable that the type should engage the work sheet with substantially the same force when the parts of said mechanism are in upper case positions as when they are in lower case positions. In order to secure this result, the parts of the type bar mechanism are constructed and arranged as shown in Figs. 14 and 15, in which the roll 62, the lever 56, the link 54 and the lever 46 are illustrated diagrammatically. These figures respectively show the above parts in the positions which they assume in upper case and lower case positions and the said parts are illustrated in full lines in type bar retracted positions and in dot and dash lines in positions substantially at the end of their type bar actuating movement. Taking the line 94 extending from the center 93 of the pivot 73 through the center of the pivotal connection 88, with the parts in type bar retracted positions, the parts are constructed and arranged so that the center of said pivotal connection is brought back to this line at the end of its type bar actuating movement both with the parts in upper case and with the parts in lower case positions. The pivotal connection 82 is located substantially the same distance from the line 94 in both lower case and upper case positions. It will be noted that the path of the pivotal connection 88 makes substantially the

same angles with the corresponding positions of the link 54 in lower case and upper case positions and substantially the same movement or force will be imparted to the type bar.

5 Figs. 1 to 6 inclusive, show the type bar mechanisms arranged to impart substantially equal type impression movements to the type bar in lower and upper case positions. This construction, in actual practice, has been employed in 10 the numeral type bar mechanisms, in which the upper case figure type impression surfaces have substantially the same areas as the corresponding lower case figure types.

Figs. 16 and 17 show diagrammatically, the roll 15 62, the lever 56, the link 54 and the lever 46 constructed and arranged to impart a greater movement to the type bar to cause a heavier type impression when the parts of the type bar mechanism are in upper case position than when said 20 mechanism is in lower case position. Fig. 16 shows the parts of the mechanism in upper case positions and Fig. 17 shows the parts in lower case positions, with the parts in full lines in type bar retracted positions and in dot-and-dash lines 25 at substantially the end of their type bar actuating movement. Again, taking the line 94 extending from the center 93 of the pivot 73 through the center of the pivotal connection 88 with the parts in type bar retracted positions, 30 the parts are constructed and arranged so that the center of said connection 88 is not brought back to the line 94 at the end of the type bar actuating movement in either the upper case or the lower case position of the parts but the 35 final position of said center is below said line as clearly shown. In this case, the pivotal connection 82 is located at the same distance from the line 94 on opposite sides of said line in lower and upper case positions of the parts, as in Figs. 14 and 15. With this construction, the path of the center of said pivotal connection 88 lies at a greater angle to the positions of the link 54 when the parts are in lower case positions than when the parts are in upper case positions and the type 40 bar will be given a greater movement to cause a heavier type impression when the parts are in upper case positions.

Fig. 18 discloses a modified construction by 50 which the strengths of the type impressions may be regulated. In this construction the lever 56 consists of two parts of which one part 56a is pivoted on the pivot rod 58 and a second part or arm 56b is adjustably mounted on the part 56a. The part 56b is formed with a slot 244 in which 55 engages a holding bolt or screw 246 passing through an opening in the part 56a and the part 56b is provided with a second slot 248 in which engages a boss or stud 56c formed on the part 56a, the part 56b being secured to the part 56a by the screw or bolt 246.

By means of the above construction, the downwardly extending arm of the bell crank 56 may be lengthened or shortened to adjust the length of the type impression stroke imparted to the type bar 22 thereby to adjust the heaviness of the type impression.

The type bars, when retracted, are placed in a forwardly opening arcuate assemblage and they normally occupy the substantially upright position shown in Figs. 1, 2 and 3 with their upper ends against the arcuate buffer ring 79. This buffer ring is carried by arms 81 extended upwardly from the plates 68 connecting the type bar segment 14 and the support 26 and by a supporting plate 83 mounted at its lower end in slots

85 and 87 in the segment 14 and the support 26 and having its upper end attached to said buffer ring. The buffer ring 79 supports a pad 89 of any suitable material arranged to be engaged by the type bars when said bars are in retracted positions.

The present type actions are similar in certain respects, to the type actions shown and described in the patents to Foothorap Nos. 1,251,361 dated December 25, 1917, and 1,681,978 dated August 28, 1928, and contain the primary objectives of slow and easy starting movement of the type bar, accelerated movement thereof as it approaches the printing point, locking of the bar against rebound at the end of its retracting movement and smooth operation. As a type bar mechanism is started on a type impression stroke from the position shown in Figs. 1, 2 and 3, the arc of movement of the pivotal connection 101 between the link 38 and the lever 32 is very nearly perpendicular to the arc of movement of the pivotal connection 102 between the link 38 and the type bar 22 and, as the type bar descends, the paths of movement of the connections 101 and 102 become more nearly aligned. Therefore, the type bar will be started smoothly and easily and its movement will be accelerated as it approaches the work.

The tendency of the type bar to rebound from the buffer ring 79 is prevented by the substantially locking relation of the pivotal connection 102, the pivotal connection 101 and the pivot 34 of the lever 32 which are substantially in alignment at this time.

The parts of the type bar mechanism are constructed and arranged so that, during a type impression stroke of a type bar, the pawl 120 is disengaged from the fluted roll 118 when the type is a substantial distance from the work sheet and the type bar then executes the remainder of its stroke under the momentum of the parts of the type bar mechanism. The point in the movement of a type bar at which the pawl is disengaged from the fluted roll may be regulated to vary the force with which the type is engaged with the work sheet by the adjustment of the plate 132.

The present machine has a high degree of visibility combined with the advantages of the shiftable type segment for shifting case.

It is to be understood that, except as defined in the claims, the invention is not limited to the particular construction and arrangement of parts of the illustrated embodiment of the invention but that the invention may be embodied in other forms within the scope of the claims.

Having explained the nature and object of the invention and having illustrated and described a construction embodying the invention in its preferred form, what is claimed is:

1. In a typewriting machine, a horizontally arranged substantially flat platen, a pivoted type bar segment, a series of type bars pivoted on said segment and having their axes arranged in an arc having its center adjacent the typing point, types mounted on each type bar and arranged to engage a work sheet at the end of a down stroke of the type bar, a series of second levers pivoted on said segment upon axes arranged in an arc substantially parallel with said first arc, links, each pivotally connected directly with a type bar and with one of the second levers, through which the type bars are actuated, respectively, from the second levers, a series of third levers pivoted on said segment upon axes arranged

in a substantially straight line, operating connections respectively between said second levers and said third levers, mechanism for actuating said third levers respectively to actuate the type bars and means for moving said type bar segment to shift case.

2. In a typewriting machine, a horizontally arranged substantially flat platen, a pivoted type bar segment, type bars pivoted on said segment and each having two types thereon each arranged to engage a work sheet at the end of a down stroke of the type bar, a series of second levers pivoted on said segment and all having substantially the same dimensions, a series of links respectively connecting said second levers with said type levers, a series of third levers pivoted on said segment and varying in dimensions from the center to the sides of said segment, a series of links respectively connecting said second levers with said third levers, means for actuating said third levers to actuate the type bars and means for shifting said type bar segment.

3. In a typewriting machine, a horizontally arranged substantially flat platen, a pivoted type bar segment, a series of type bars pivoted on said segment upon axes arranged in an arc having its center adjacent the typing point, types mounted on each type bar and arranged to engage a work sheet at the end of a down stroke of the type bar, a series of second levers all of substantially the same dimensions pivoted on said segment upon axes arranged in an arc substantially parallel with said first arc, a series of links connecting said second levers with said type levers, a series of third levers pivoted on said segment upon axes arranged substantially in a straight line and said levers varying in dimensions from the center to the sides of said segment, connections respectively between the second levers and the third levers for operating the second levers, means for actuating said third levers to actuate the type bars and means for moving said type bar segment to shift case.

4. In a typewriting machine, a horizontally arranged substantially flat platen, a pivoted type bar segment, a type bar pivoted on said segment, types mounted on said type bar and arranged to engage a work sheet at the end of a downward stroke of the type bar, a second lever pivoted on said segment, a link connecting the type bar with the second lever, a third lever pivoted on said segment, a link connecting the second lever and the third lever, a fourth lever pivoted independently of said segment, a link connecting the third lever and the fourth lever, a fifth lever pivoted independently of said segment, an operative connection between the fifth lever and the fourth lever for operating the fourth lever from the fifth lever and means for shifting said segment and thereby shifting the pivotal connection between the third link and third lever from a position on one side of a line connecting the axis of the segment with the pivotal connection between said link and the fourth lever to a position on the other side of said line at substantially the same distance therefrom.

5. In a typewriting machine, a horizontally arranged substantially flat platen, a pivoted type bar segment, a series of type bars pivoted on said segment and each having types arranged to engage a work sheet at the end of a down stroke of the type bar, a series of second levers pivoted on said segment and having substantially the same dimensions, a series of links respectively connecting the second levers with the type bars.

a series of third levers pivoted on said segment and varying in dimensions from the center to the sides of the segment, a series of links respectively connecting the third levers with the second levers, a series of fourth levers pivoted independently of said segment and having their arms connected with the third levers of decreasing lengths from the central part to the sides of the segment, a series of links connecting said fourth levers with said third levers, a series of fifth levers pivoted independently of said segment, operative connections respectively between the fifth levers and the fourth levers located at different distances from the axes of the fourth levers, means for actuating the fifth levers to actuate the corresponding type bars and means for shifting said type bar segment.

6. In a typewriting machine, a horizontally arranged substantially flat platen, a pivoted type bar segment, a series of type bars pivoted on said segment upon axes arranged in an arc having its center adjacent the typing point, types mounted on each bar and arranged to engage a work sheet at the end of a down stroke of the type bar, a series of second levers pivoted on said segment upon axes arranged in an arc substantially parallel with said first arc, a series of links respectively connecting said second levers and said type levers, a series of third levers pivoted on said segment upon axes arranged substantially in alignment, a series of links connecting said third levers and said second levers, a series of fourth levers pivoted independently of said segment upon axes arranged substantially in a straight line, a series of links connecting said fourth levers and said third levers, means for actuating said fourth levers to actuate the type bar and means for moving said type bar segment to shift case.

7. In a typewriting machine, a horizontally arranged substantially flat platen, a pivoted type bar segment, a series of type bars pivoted on said segment upon axes arranged in an arc, types mounted on each bar and arranged to engage a work sheet at the end of a down stroke of the type bar, a series of second levers pivoted on said segment upon axes arranged in an arc substantially parallel with said first arc, a series of links respectively connecting said second levers and said type levers, a series of third levers pivoted on said segment upon axes arranged substantially in a straight line substantially parallel to a line tangent to the latter arc, a series of links connecting said third levers and said second levers, a series of fourth levers pivoted independently of said segment upon axes arranged substantially in a straight line, a series of links connecting said fourth levers and said third levers, means for actuating said fourth levers to actuate the type bar and means for shifting said type bar segment.

8. In a typewriting machine, a horizontally arranged substantially flat platen, a pivoted type bar segment, a series of type bars pivoted on said segment upon axes arranged in an arc, a series of second levers pivoted on said segment upon axes arranged in an arc substantially parallel with said first arc, a series of links respectively connecting said second levers and said type levers, a series of third levers pivoted on said segment upon axes arranged substantially in a straight line substantially parallel to a line tangent to the latter arc, a series of links connecting said third levers and said second levers, a series of fourth levers pivoted independently of said segment upon axes arranged substantially in a

straight line substantially parallel to the latter line, a series of links connecting said fourth levers and said third levers, means for actuating said fourth levers to actuate the type bar and means for shifting said type bar segment to change case.

9. In a typewriting machine, a horizontally arranged substantially flat platen, a type bar segment shiftable toward and from the platen, a series of type bar mechanisms each comprising a type bar pivoted on said segment, types mounted on said bar and arranged to engage a work sheet at the end of a down stroke of the type bar, a second lever pivoted on said segment, a link 10 connecting the type bar and said second lever, a third lever pivoted on said segment, a link connecting the third lever and the second lever, a fourth lever pivoted independently of said segment, a link connecting the fourth lever and the third lever and means for shifting the segment thereby shifting the pivotal connection between the link and the third lever from a position on one side of the median line of the type bar mechanism to a position on the other side of said line at substantially the same distance therefrom.

10. In a typewriting machine, a substantially flat platen, a type bar segment, a series of type bar mechanisms comprising type bars pivoted on said segment upon axes arranged in an arc having its center adjacent the typing point, types mounted on each type bar and arranged to engage a worksheet supported on the platen at the end of a stroke of the type bar, in which the type is moving in a direction substantially perpendicular to the platen, a series of second levers pivoted on said segment upon axes arranged on an arc substantially parallel with said first arc, operating connections respectively between said second levers and the type levers, a series of third levers 20 pivoted on said segment upon axes arranged in a substantially straight line, operating connections respectively between said second levers and said third levers, mechanism for actuating said third levers respectively to actuate the type bars selectively, means for supporting said type bar segment for movement with relation to the platen to shift case and means for imparting case shifting movements to said segment.

11. In a typewriting machine, a substantially flat platen, a type bar segment, a series of type bar mechanisms comprising type bars pivoted on said segment upon axes arranged in an arc having its center adjacent the typing point, types mounted on each type bar and arranged to engage a worksheet supported on the platen at the end of a stroke of the type bar, in which the type is moving in a direction substantially perpendicular to the platen, a series of second levers pivoted on said segment upon axes arranged on an arc substantially parallel with said first arc, links, each pivotally connected directly with a type bar and with one of the second levers, through which the type bars are actuated, respectively, from the second levers, a series of third levers pivoted on said segment upon axes arranged in a substantially straight line, links, each pivotally connected directly with a second lever and with a third lever, through which the second levers are actuated, respectively, from the third levers, mechanism for actuating said third levers respectively to actuate the type bars selectively, means for supporting said type bar segment for movement with relation to the platen to shift case and means for imparting case shifting movements to said segment.

12. In a typewriting machine, a substantially flat platen, a type bar segment, a series of type bar mechanisms comprising type bars pivoted on said segment upon axes arranged in an arc having its center adjacent the typing point, types mounted on each type bar and arranged to engage a worksheet supported on the platen at the end of a stroke of the type bar, in which the type is moving in a direction substantially perpendicular to the platen, a series of second levers pivoted on said segment upon axes arranged on an arc substantially parallel with said first arc, and all having substantially the same dimensions, operating connections respectively between said second levers and the type levers, a series of third levers pivoted on said segment upon axes arranged in a substantially straight line, and varying in dimensions from the center to the sides of said segment, operating connections respectively between said second levers and said third levers, mechanism for actuating said third levers respectively to actuate the type bars selectively, means for supporting said type bar segment for movement with relation to the platen to shift case and means for imparting case shifting movements to said segment.

13. In a typewriting machine, a substantially flat platen, a type bar segment, a series of type mechanisms comprising type levers pivoted on said segment, and having their axes arranged in an arc the center of which is adjacent the typing point, types mounted on each type bar and arranged to engage a work sheet supported on the platen at the end of a stroke of the type bar when the type is moving in a direction substantially perpendicular to the plane of the platen, a series of second levers pivoted on said segment upon axes arranged in an arc substantially parallel with said first arc, operating connections between said type levers and said second levers, a series of third levers pivoted on said segment, operating connections between the second levers and the third levers, mechanism for actuating the third levers respectively to actuate the type levers selectively, means for supporting said type bar segment for movement with relation to the platen to shift case and means for imparting case shifting movements to said segment.

14. In a typewriting machine, a substantially flat platen, a type bar segment, a series of type bar mechanisms comprising type bars pivoted on said segment and respectively having type heads each arranged to move in a direction substantially perpendicular to the plane of the platen adjacent the end of a type impression stroke of the corresponding type bar, types mounted on each type head and arranged to engage a work sheet supported on the platen, a series of second levers pivoted on said segment, operating connections between the type bars and the second levers, a series of third levers pivoted on said segment, operating connections between the second levers and the third levers, mechanism for actuating said third levers respectively to actuate the type bars selectively, means for supporting said type bar segment for movement with relation to the platen to shift case and means for imparting case shifting movements to said segment.

15. In a typewriting machine, a substantially flat platen, a type bar segment, a series of type bar mechanisms comprising type bars pivoted on said segment and respectively having type heads each arranged to move in a direction substantially perpendicular to the plane of the platen

adjacent the end of a type impression stroke of the corresponding type bar, types mounted on each type head and arranged to engage a work sheet supported on the platen, a series of second levers pivoted on said segment and having their axes arranged in a circular arc, operating connections between said type bars and said second levers, a series of third levers pivoted on said segment and having their axes arranged in a substantially straight line, operating connections between said second levers and said third levers, mechanism for actuating said third levers respectively to actuate selectively the type bars, means for supporting said type bar segment with relation to the platen to shift case and means for imparting case shifting movements to said segment.

16. In a typewriting machine, a substantially flat platen, a type bar segment, a series of type mechanisms comprising type levers pivoted on said segment, types mounted on each type lever and arranged to engage a work sheet supported on the platen at the end of a stroke of the type lever in which the type is moving in a direction substantially perpendicular to the plane of the platen, a series of second levers pivoted on said segment and having their axes arranged in a circular arc, said second levers all having substantially the same dimensions, operating connections between said type levers and said second levers, a series of third levers pivoted on said segment and having their axes arranged in a substantially straight line, said third levers varying in dimensions from the center to the sides of said segment, operating connections between said second levers and said third levers, mechanism for actuating said third levers respectively to actuate selectively the type bars, means for supporting said type bar segment for movement with relation to the platen to shift case and means for imparting case shifting movements to said segment.

17. In a typewriting machine, a substantially flat platen, a type bar segment, a series of type bar mechanisms comprising type bars pivoted on said segment, and respectively having type heads each arranged to move in a direction substantially perpendicular to the plane of the platen adjacent the end of a type impression stroke of the corresponding type bar, types mounted on each type head and arranged to engage a work sheet supported on the platen, a series of second levers pivoted on said segment, and all having substantially the same dimensions, operating connections between the type bars and the second levers, a series of third levers pivoted on said segment, and varying in dimensions from the center to the sides of said segment, operating connections between the second levers and the third levers, mechanism for actuating said third levers respectively to actuate the type bars selectively, means for supporting said type bar segment for movement with relation to the platen to shift case and means for imparting case shifting movements to said segment.

18. In a typewriting machine, a platen, a type bar segment shiftable with relation to the platen, a series of type bar mechanisms each comprising a type bar pivoted on said bar, a second lever pivoted on said segment, means comprising a link connecting the type bar and said second lever, a third lever pivoted independently of said segment, means including a link connecting the latter lever and the second lever, means for shifting the segment and

thereby shifting the pivotal connection between the latter link and the second lever from a position on one side of the median line of the type bar mechanism to a position on the other side of said line at substantially the same distance therefrom and means for actuating the third lever to actuate the type bar, the parts being constructed and arranged so that the pivotal connection between the latter link and the third lever moves at a substantial angle to said line during the actuation of the third lever to actuate the type bar.

19. In a typewriting machine, a platen, a type bar segment shiftable with relation to the platen, a series of type bar mechanisms, each comprising a type bar pivoted on said segment, types mounted on said bar, a second lever pivoted on said segment, means comprising a link connecting the type bar and said second lever, a third lever pivoted independently of said segment, means including a link connecting the latter lever and the second lever, means for shifting the segment and thereby shifting the pivotal connection between the latter link and the second lever from a position on one side of the median line of the type bar mechanism to a position on the other side of said line at substantially the same distance therefrom, and means for actuating the third lever to actuate the type bar, the parts being constructed and arranged so that the pivotal connection between the latter link and the third lever moves at a greater angle to said line during the actuation of the latter lever to actuate the type bar when the type bar mechanism is in lower case position than when said mechanism is in upper case position.

20. In a typewriting machine, a platen, a type bar segment shiftable toward and from the platen, a series of type bar mechanisms, each comprising a type bar pivoted on said segment, types mounted on said bar, a second lever pivoted on said segment, means comprising a link connecting the type bar and said second lever, a third lever pivoted independently of said segment, means including a link connecting the latter lever and the second lever, mechanism for actuating the latter lever to actuate the type bar, and means for shifting the segment and thereby shifting the pivotal connection between the latter link and the second lever from a position on one side of the median line of the type bar mechanism to a position on the other side of said line at substantially the same distance therefrom, and means for actuating the third lever to actuate the type bar, the parts being constructed and arranged so that the pivotal connection between the latter link and the third lever moves to a position in said line at the end of a type bar actuating stroke of the third lever when the type bar mechanism is in both upper case and lower case positions.

21. In a typewriting machine, a substantially flat platen, a type bar support, a series of type bars pivoted on said support and each having a type arranged to engage a worksheet supported on the platen at the end of a stroke of the type bar in which the type is moving in a direction substantially perpendicular to the platen, a series of second levers all having substantially the same dimensions, a series of links respectively connecting the second levers with the type bars, a series of third levers varying in dimensions from the center toward the sides of the series, a series of operating connections respectively between the third levers and the second levers, a series of

fourth levers having their arms respectively connected with the third levers of decreasing lengths from the center portion to the sides of the series, a series of links respectively connecting the fourth levers with the third levers, and means for actuating the fourth levers to actuate respectively the corresponding type bars.

22. In a typewriting machine, a substantially flat platen, a type bar support, a series of type bars, pivoted on said support upon axes arranged in an arc, a type mounted on each bar and arranged to move in a direction substantially perpendicular to the plane of the platen adjacent the end of a type impression stroke of the corresponding type bar, a series of second levers pivoted upon axes arranged in an arc substantially parallel with said first arc, a series of links respectively connecting said second levers and said type levers, a series of third levers pivoted upon axes arranged substantially in a straight line parallel to a tangent to the latter arc, a series of operating connections respectively between said third levers and said second levers, a series of fourth levers pivoted upon axes arranged substantially in a straight line parallel to the latter line, a series of links respectively connecting said fourth levers and said third levers and means for actuating said fourth levers to actuate the type bars.

23. In a typewriting machine, a substantially flat platen, a forwardly opening segmental series of radially disposed pivoted type bars normally located substantially perpendicular to the platen, a series of second levers, links respectively connecting the second levers with the type bar, a series of third levers, operating connections respectively between the third levers and the second levers, a series of bell cranks respectively for actuating the third levers, a series of links, each pivotally connected directly with one of the bell cranks and with a third lever, a series of parallel levers pivoted at their rear ends upon axes arranged substantially in a straight line, said levers extending forwardly from their axes, and operating connections respectively between the parallel levers and the corresponding bell cranks to actuate the bell cranks and thereby to actuate the type bars.

24. In a typewriting machine, a substantially flat platen, a shiftable type bar segment, a forwardly opening segmental series of radially disposed type bars pivoted on said segment to swing forwardly and downwardly during their type impression strokes upon axes arranged in an arc having its center adjacent the typing point, said type bars being normally located substantially perpendicular to the platen, a series of bell crank levers pivoted independently of said segment upon fixed axes arranged substantially in a straight line, operating connections respectively between said bell crank levers and the corresponding type bars to actuate the type bars, comprising a series of intermediate levers pivoted on said segment, means for connecting the intermediate levers respectively with the type bars, means for connecting the bell cranks respectively with the intermediate levers, a series of parallel levers pivoted at their rear ends upon axes arranged substantially in a straight line, said parallel levers extending forwardly from their axes and operating connections between the bell crank lever and the parallel levers for actuating said bell crank levers.

MILES H. MANN.
